attorney.

UNITED STATES PATENT OFFICE

ANTHONY BIANCHINI, OF SAN FRANCISCO, CALIFORNIA, ASSIGNEE OF ONE-HALF TO
LOUIS TADDEUCCI, OF SAN FRANCISCO, CALIFORNIA

BRUSH

Application filed April 18, 1930. Serial No. 445,471.

This invention relates to improvements in brushes, and has particular reference to a fountain brush.

The principal object of this invention is to produce a brush wherein a quantity of plaster or other similar material may be carried in a reservoir attached to the brush and fed to the brush as desired.

A further object is to produce a brush which is easy to handle and one which is manipulated in the customary manner.

A further object is to produce a brush wherein the same will not become easily clogged.

15 A further object is to produce a brush of this character which is economical to manufacture.

Other objects and advantages will be apparent during the course of the following description.

In the accompanying drawing forming a part of this specification and in which like numerals are employed to designate like parts throughout the same,

25 Figure 1 is a side elevation of my brush with the valves in open position,

Figure 2 is a vertical cross section of my brush showing the valves in close position,

Figure 3 is a side elevation of my brush,

30 Figure 4 is a cross sectional view taken on the line 4-4 of Figure 1, and

Figure 5 is a cross sectional view taken on the line 5-5 of Figure 1.

In using an ordinary paint brush, it is customary to dip the bristles of the brush into the paint or plaster to be applied, and to then apply the plaster upon the surface which is to receive the same. This procedure results in a considerable delay and it is often difficult for the user to reach the bucket or plaster, particularly, when working on a ladder, trestle, or scaffold. Applicant has therefore devised a brush wherein the plaster is stored in a receptacle formed within the head of the brush.

In the accompanying drawings wherein for the purpose of illustration is shown a preferred embodiment of my invention, the numeral 5 designates the handle of the brush which is secured to a ferrule 6 which is in

turn secured to the top 7 of a receptacle 8. In the bottom of this receptacle, the bristles 9 are secured in any convenient manner.

In order to fill the receptacle I have provided an opening 11 which is closed by a cap 12 carried upon a pivoted lever 13 pivoted as at 14 to the ferrule 6. A link 16, pivoted as at 17, has its lower end connected to a rocker arm 18, which carries a pawl 19 which engages the teeth of a ratchet 21, carried upon a valve rod 22, which is hollow as best shown in Figure 4, and extends across the receptacle 8 as best shown in Figure 2. This rod has openings 23 formed therein which are in alignment with the opening 24 formed in a cross piece 26 embedded in the head of the bristles.

The result of this construction is that when a fluid, such as plaster, is placed in the receptacle 8, the same will be held therein until the user actuates the lever 13 which raises the cap 12 and turns the valve rod 22 through the action of the link 16 and pawl 19 engaging the ratchet 21. As soon as sufficient plaster has entered the bristles through the opening 23 in the valve rod, a second actuation of the lever 13 will close the valve rod, and the plastering may proceed.

By combining the action of the valve rod with the lifting of the cap 12 any vacuum which would be created in the receptacle, which would tend to retard the flow will be prevented.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

Having thus described my invention, I claim:

In a device of the character described, a handle, a receptacle secured to said handle, bristles secured to said receptacle, a tubular valve interposed between said receptacle and said bristles, ports formed thru said tubular valve, the ports on the opposite sides of said valve being in alignment with each other, a

ratchet secured to said tubular valve, a lever connected to said handle, an opening formed in said receptacle, a cap secured to said lever and adapted to close said opening, a link pivoted to said lever, a ratchet arm pivoted to said receptacle and to said link and adapted to engage said ratchet.

5 In testimony whereof I affix my signature.

ANTHONY BIANCHINI.
